UNITED STATES PATENT OFFICE.

GEORGE E. WILBUR, OF TAUNTON, MASSACHUSETTS, ASSIGNOR TO THE
WEIR STOVE COMPANY, OF SAME PLACE.

DESIGN FOR A RANGE OR COOKING-STOVE.

SPECIFICATION forming part of Design No. 32,010, dated December 19, 1899.

Application filed November 10, 1899. Serial No. 736,543. Term of patent 14 years.

To all whom it may concern:

Be it known that I, GEORGE E. WILBUR, a citizen of the United States, residing at Taunton, in the county of Bristol and State of Massachusetts, have invented and produced a new and original Design for Ranges or Cooking-Stoves, of which the following is a specification, reference being had to the accompanying drawing, forming a part thereof.

10 The figure represents in perspective a range having my new design.

The leading or material features of my design reside in the general outline and shape of the range and in its special ornamentation.

15 The outline is best represented by the drawing and is largely a matter of proportion of parts and their general lines. The ornamentation comprises the effects produced upon the surfaces thus obtained and which emphasize such features.

20 One of the principal effects obtained is that of rich plainness, produced by the unornamented central sections of the two main panels or doors and by the heavy plain edges to the two shelves and the

25 relatively plain but heavy ornamental effects about these plain sections, which tend to emphasize the plain sections rather than to detract from them. There may be said to be five principal effects obtained. One is by

30 means of the borders—the border *a* to the top of the range, the border *a'* to the hearth, and the border *a²* to the shelf. The others are produced by the doors *b*, *c*, *d*, and *e*. The

door *b* is the oven-door. It has the plain central section *b'*, upon which is mounted the 35 name-plate *b²*. This name-plate is shaped and ornamented as represented in the drawing. The corners of the oven-door are ornamented with rich leaf effects or scrolls, which extend from each corner in branches horizontally along the top and bottom edges and vertically along the sides, and they are combined with a slight molding-and-bead effect. The door *c* has at each corner a conventional leaf scroll, the upper of which extends downward 45 and the lower upward, and the scrolls are connected at the top and at the bottom by a connecting figure in the nature of a leaf. The door *d* and its supports *d'* are likewise ornamented with heavy leaf-scroll effects, as 50 represented in the drawing, and the same is true of the door *e*.

The entire ornamentation of all the doors is of the same general character, although the designs are not entirely alike, but are 55 modified to give a pleasing variety.

Having thus described the design and its essential parts, what I claim as new, and desire to secure by Letters Patent, is—

60 The design for a range or cooking-stove as herein shown and described.

GEO. E. WILBUR.

In presence of—

F. F. RAYMOND, 2d,
J. M. DOLAN.
